[57] CLAIM

The ornamental design for a bathing pool, substantially as shown.

DESCRIPTION

FIG. 1 is a top perspective view of a bathing pool showing our new design;

FIG. 2 is a cross-section taken on line 2—2 of FIG. 1 with portions omitted for ease of illustration;

FIG. 3 is a cross-section similar to FIG. 2 taken on line 3—3 of FIG. 1;

FIG. 4 is a cross-section similar to FIG. 2 taken on line 4—4 of FIG. 1; and

FIG. 5 is a bottom plan view thereof.
